(57) **CLAIM**

I claim the ornamental design for rear fog lamp for automobile, as shown and described.

DESCRIPTION

FIG. 1 is a front perspective view of the rear fog lamp;

FIG. 2 is a front elevation view of the rear fog lamp;

FIG. 3 is a back elevation view of the rear fog lamp;

FIG. 4 is a left side plan view of the rear fog lamp;

FIG. 5 is a right side plan view of the rear fog lamp;

FIG. 6 is a top plan view of the rear fog lamp; and,

FIG. 7 is a bottom plan view of the rear fog lamp.

The rear fog lamp for automobile is constructed from synthetic resin and glass, and would be affixed at the rear of an automobile.
